UNITED STATES PATENT OFFICE.

HENRY O. SCHMIDT, OF NEW YORK, N. Y., ASSIGNOR TO SIMONS, BROTHER & CO., OF PHILADELPHIA, PENNSYLVANIA.

DESIGN FOR A CANE OR UMBRELLA HANDLE.

SPECIFICATION forming part of Design No. 19,985, dated July 1, 1890.

Application filed April 15, 1890. Serial No. 348,110. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

15 A is the body part, and extends upward and over into the crook B, and is provided with the heel-extension C. This heel-extension is ornamented by a series of curved and substantially-horizontal grooves D, which vanish as they approach the main portion of the crook B; but the lower portions of said grooves are 20 finished near the end of the crook B, in the ribs E, extending over top, and in the orna-

mental work F, extending along and returning upon the end part of the crook. The main part of this body, crook, and heel-extension is plain, but may be of shaded work, 25 if desired. The lower part of the body A is finished with an annular band G of ornamental work.

The handle is made of any suitable material.

Having now described my new design, what I claim as new, and desire to secure by Letters Patent, is—

25 The design for cane or umbrella handles, substantially as herein described and shown.

30 In testimony of which invention I have hereunto set my hand.

HENRY O. SCHMIDT.
